UNITED STATES PATENT OFFICE.

ANTONIO HORCASITAS AND MIGUEL RUELAS, OF LOS ANGELES, CALIFORNIA.

BRACELET-CASE.

1,264,650.

Specification of Letters Patent. Patented Apr. 30, 1918.

Application filed May 15, 1916. Serial No. 97,721.

To all whom it may concern:

Be it known that we, ANTONIO HORCASITAS and MIGUEL RUELAS, Mexican citizens, residents of Los Angeles, county of Los Angeles, State of California, have invented new and useful Improvements in Bracelet-Cases, of which the following is a specification.

This invention has reference generally to improvements in that class of inventions known as special article carriers and more particularly relates to a bracelet case.

It is the principal aim and object of this invention to provide a device of the character mentioned designed for receiving and hermetically sealing a watch to isolate the same from the elements, thus permitting of the use of the watch whether the wearer be in bathing or working in dusty mines, etc.

As an additional object this invention contemplates the provision of a bracelet case for watches with sides protecting the same from the action of the elements and thus affording safety and security for the workman or swimmer, and which permits of a watch being readily seen so that it is unnecessary to open the case to determine the time, the dial of the watch being always visible through the case.

More particularly this invention includes the provision of a sectional case within which is removably clamped a watch and with which cooperates wrist encircling means for supporting the case upon the wrist of the wearer.

A more specific object of this invention consists in the provision of common means between the watch case and the cover of the bracelet case for hermetically sealing the bracelet case and for protecting the crystal of the watch; to also provide means for removably locking the sections of the case to permit of the removal of the watch therefrom without detaching the wrist engaging means.

Among the other aims and object of this invention may be recited the provision of a device of the character described with a view to compactness, and in which the number of parts are few, the construction simple, the cost of production low and the efficiency high.

Other improvements and novel details in the construction and arrangement of the various parts of the apparatus will be brought out more in detail in the description to follow, which for a clear understanding of the invention should be considered in

connection with the accompanying drawings forming a part hereof, and wherein is disclosed for the purpose of illustration a convenient and satisfactory embodiment of the invention. It is to be noted in this connection that minor changes in the construction and arrangement of parts may be made without departing from the principle of operation of the various parts.

The invention is clearly illustrated in the accompanying drawings; in which:

Figure 1 is a top plan view showing the watch in position on the wrist of the wearer; 70

Fig. 2 is a transverse section of the invention, the wrist strap being shown in elevation;

Fig. 3 is an elevational detail of the band;

Fig. 4 is a bottom plan view of the device; 75

Fig. 5 is a bottom plan view of the cover;

Fig. 6 is a top plan view of the washer;

Fig. 7 is a top plan view of the base;

Fig. 8 is a top plan view of another form 80 of the invention in position on the wrist of the wearer;

Fig. 9 is a transverse section thereof;

Fig. 10 is a transverse sectional view showing the latch in an open position; 85

Fig. 11 is a bottom plan view showing the watch case disengaged from the wrist strap;

Fig. 12 is a bottom plan view of the cover;

Fig. 13 is a modified top plan view of the washer; 90

Fig. 14 is a modified top plan view of the base.

Similar characters of reference are employed in all the above described views to indicate corresponding parts. 95

Referring now, more particularly, to the accompanying drawings there is provided a disk-like base 1 formed of any suitable material such as hard rubber, metal, etc., being threaded exteriorly as indicated by the numeral 2 for a purpose that will presently appear. The upper surface of the base is provided with a watch receiving recess 3 for removably accommodating a watch 4 of any conventional construction, the stem 5 of 105 which is also removably accommodated in a stem receiving recess 6 in the base and communicating with the recess 3.

With a view toward providing improved means for removably holding the watch 4 110 on the base 1 and for hermetically sealing the watch casing within the recess, an annular cushion such as a rubber washer 7 is disposed on the peripheral edge of the base

while a transparent cover 8 having a depending flange 9 is removably engaged on the threads 2 through the instrumentality of the inner surface of the flanged portion 9 so that 5 the cover will act against the cushion which in turn coöperates with the disk-like base in clamping the watch in substantial stationary position within the case formed by the base and the cover. The under surface of 10 the base is preferably provided with opposed recesses 11 for accommodating the fingers of the wearer to facilitate the application of the cover to the base.

As intimated, improved means have been 15 provided on the cover for coöoperating with the wrist engaging means. In reducing this feature of the invention to practice the flanged portion 9 is provided with an annular groove 12 on its outer surface in which is 20 terminally fixed an annular metallic reinforcing band 13. Loops 14 depend from opposite points on the band and project beneath the lower surface of the base and lie within opposed pairs of slots 15 in the flange 25 so as to prevent relative rotary movement of the band and the cover. A wrist encircling strap 16 is now engaged in the loops while a buckle 17 of any conventional design is carried on the outer end thereof for adjustably 30 and removably connecting the free ends of the strap about the wrist of the wearer.

In Figs. 8 to 14 inclusive there is shown a modified form of the invention. Although the preferred construction affords safety and 35 security for the workman and the swimmer, it does not permit the removal of the watch without removing the wrist encircling strap and inasmuch as there are cases where facility for handling the watch is preferred the 40 following modification has been provided. In this instance instead of employing the annular band for connecting the loops to the cover, loops 18 are mounted at opposite points on the under surface of the base 19 for 45 slidable arrangement about a wrist strap 20 similar in construction to the wrist strap 16. A threaded stud 21 is anchored in the under surface of the base 19 while a latch bar 22 is pivotally connected thereto and is 50 removably arranged in a radial groove 23 in the under surface of the base while a catch 24 on the outer end of the latch bar is 55 removably arranged in a recess 25 on the outer periphery of the flanged portion 26 of the cover 27. Normally when in the position shown in Fig. 9 the wrist of the wearer coöperates with the wrist strap 20 in holding the latch bar in such position. However, it is to be appreciated that by removing 60 the catch 24 on the end of the bar 22 from the recess 25 the transparent cover 27 may be removed to consequently permit of the removal of the annular cushion 28 from en-

gagement with the watch 29 seated in the upper surface of the base without detaching 65 the wrist strap.

It is believed in view of the foregoing description that a further detail description of the operation of the invention is entirely unnecessary. Likewise it is thought the advantages of the invention will be readily apparent. However, it may be mentioned that the flanged cover being formed of a transparent material such as glass enables the wearer of the watch to look through the 75 same to determine the time whenever it is desired. In addition the coöperation between the base, the cover and the cushion or washer assures that the watch will be protected from the action of the elements so 80 that persons working in mines, factories, railroads, etc., and in general in all places where the atmosphere is full of dust or moisture may conveniently use the case.

As many changes could be made in the 85 above construction and many apparently widely different embodiments of this invention could be made without departing from the scope of the latter, it is intended that all matter contained in the above description or shown in the accompanying drawings shall be interpreted as merely illustrating the conception of our invention. These and other modifications are intended to be covered by the present claim. 95

Having thus fully described this invention, what is claimed as new and desired to be secured by Letters-Patent, is:—

In a device of the kind described, in combination, an annular base portion, having 100 a threaded edge, a concavo-convex cover threaded onto the threaded edge of said base portion, a pair of oppositely-extending loop members mounted on the under surface of said base portion, one of said loops having its inner portion secured to said base portion at a point spaced inwardly of the threaded edge thereof, a stud anchored in the under surface of said base portion, a latch bar pivoted to said stud, said base portion being formed with a radial groove in which said latch bar is received and said cover being formed upon its peripheral edge with a recess, a catch formed terminally upon said latch bar adapted to project into 110 said recess to lock said cover against rotation, and a strap passed through said loop members and adapted when its ends are secured together, to press against said latch bar so as to retain the latter within said 115 groove. 125
